TOOTHBRUSH HOLDER, TIMER OR SIMILAR DEVICE

Richard W. Dobyns, 1351 Graymill Drive,
Scotch Plains, N.J. 07076

Filed July 9, 1973, Ser. No. 377,423

Term of patent 14 years

Int. Cl. D6—04

U.S. Cl. D6—94

FIG. 2

FIG. 1 is a front perspective view of a toothbrush holder, timer or similar device, showing my new design; FIG. 2 is a left side view thereof; and

FIG. 3 is a top view thereof.

The toothbrush shown is a handle for starting the timer. I claim:

The ornamental design for a combined toothbrush holder, timer or similar device, substantially as shown and described.
